UNITED STATES PATENT OFFICE.

RUFUS R. CARTER, OF BASIL, OHIO.

CLOTHES-LINE SUPPORT.

SPECIFICATION forming part of Letters Patent No. 371,423, dated October 11, 1887.

Application filed February 12, 1887. Serial No. 227,373. (No model.)

To all whom it may concern:

Be it known that I, RUFUS R. CARTER, a citizen of the United States, and a resident of Basil, in the county of Fairfield and State of Ohio, have invented certain new and useful Improvements in Clothes-Line Supports; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved clothes line support. Fig. 2 is a central longitudinal sectional view of the same. Fig. 3 is a perspective detail view of the upper end of the support. Fig. 4 is a perspective view of the lower end of the support, showing the foot or base secured to be used as a carpet-stretcher; and Fig. 5 is a perspective view of the adjusting-lock removed from the sliding bar.

Similar numerals of reference indicate corresponding parts in all the figures.

My invention has relation to extensible supports for clothes-lines, and it contemplates certain improvements upon the support for which application was made for Letters Patent on the 25th day of August, 1886, Serial No. 211,834; and it consists to that end in the improved construction and combination of parts of such an extensible clothes-line support, as hereinafter more fully described and claimed.

In the accompanying drawings, the numeral 1 indicates the lower or stationary bar of the support, which is provided at its upper end with a loop or bearing, 2, within which the upper sliding bar, 3, fits and slides, the lower end of this sliding bar having a similar loop or bearing, 4, with which it slides upon the lower bar, the two loops or bearings thus guiding the sliding bar.

The lower end of the lower bar is beveled at both sides, as shown at 5, and a foot or base, 6, is formed with two upwardly-projecting perforated flanges or ears, 7, at its side edges, through which flanges or ears a bolt, 8, passes, which passes through a perforation, 9, in the lower end of the bar, pivoting the foot to the

said end of the bar. The ends of the foot are formed with inclined flanges 10, and one of these flanges is provided with a plate, 11, secured to the inner side of the flange and formed with outwardly-projecting curved serrations 55 or teeth 12, the said serrated or toothed plate being secured detachably to the flange.

One side of the lower end of the lower bar is formed with a transverse groove, 13, and the pivotal bolt of the foot may be removed 50 from the perforated ears of the foot and from the perforation in the end of the bar, and the foot may be placed against the side of the lower end of the bar, the ears or flanges projecting up on the sides of the bar, whereupon 65 the bolt may be inserted into the perforated ears fitting in the transverse groove in the other face of the bar, whereby the foot may be secured to the end of the bar, which may now be used as a carpet-stretcher.

One face of the lower bar is provided with a series of notches having straight upwardly-facing sides, and having the other sides beveled, as shown at 14, and the lower end of the upper sliding bar is formed with a longitudinal recess, 15, open at the end, the outer side and end of which recess is closed with a plate or casing, 16, having an outwardly-projecting handle, 17, by means of which the upper bar may be slid.

The portion of the plate covering the outer side of the recess is provided with an inwardly-projecting lug, 18, near its upper end, to which lug the upper end of a beveled pawl, 19, is pivoted, the said pawl having a downwardly-projecting lip, 20, at its lower end, which may bear against an upwardly-projecting lip, 21, upon the lower end of the plate, the said lip limiting the play of the pawl and preventing it from being forced out too far 90 from the recess.

The pawl is provided with a trigger, 22, projecting through a slot, 23, in the outer side of the plate or casing, and with a curved stud, 24, sliding outward in a perforation, 25, in the 95 plate, and having a coiled spring, 26, upon it, bearing against the pawl and against the inner side of the plate, the said spring forcing the pawl against the notched face of the lower bar and forcing it into the notches.

The upper end of the sliding bar is provided in one face with a recess, 27, consisting of a semi-cylindrical portion, 28, and an oblique upper portion, 29, having preferably a slight curve, and a block, 30, having a semi-cylindrical recess or groove, 31, in its lower side, and having its inner face shaped to correspond to the oblique and curved portion of the recess, is hinged at the lower edge of the open side of the recess, and may swing into the recess, filling the oblique and curved portion of the recess and forming a cylindrical bore by the two semi-cylindrical recess portions, a suitable turn-button, 32, being pivoted at the upper edge of the recess and fitting over the upper edge of the hinged block, the said recess serving to hold and receive the clothes-line, which may be inserted when the block is swung out and be retained when the block is swung up in place and locked by the turn-button.

It will be seen that the sliding bar may be slid up upon the lower bar and may engage the notches with the pawl, and that by tilting the trigger of the pawl the pawl may be drawn into the recess, so that the sliding bar may be drawn downward, the pawl and the beveled notches admitting of the support being extended to any desired length.

30 The serrated or toothed plate, detachably secured to the flange of the foot-plate, will allow the support to be used as a carpet-stretcher in the usual manner.

Having thus described my invention, I claim and desire to secure by Letters Patent of the 35 United States—

1. In a clothes-line support, the combination

of an extensible bar, the lower end of which is beveled upon both sides and provided with a transverse perforation, a base having two upwardly-projecting perforated flanges at its edges and oblique flanges at the ends, one of which is perforated, a serrated plate, and a bolt for securing said plate to the base, as and for the purpose shown and set forth. 40 45

2. In a clothes-line support, the combination of a lower stationary bar having notches in one face, beveled at their upper sides, an upper bar sliding upon the lower bar and formed with a recess at its lower end open at the faces 50 and end of the bar, a plate covering the open outer side and the open end of the recess and formed with an upwardly-projecting lip at the inner side of the recess, and formed with an outwardly-projecting handle and with an inwardly-projecting lug and with a slot and a perforation below the handle, a pawl pivoted with its upper end to the lug upon the plate, and having a trigger projecting through the slot in the same, and a curved rod projecting 60 through the perforation and formed with a downwardly-projecting lip bearing against the lip of the plate, and a coiled spring upon the curved rod bearing against the pawl and against the plate, as and for the purpose shown 65 and set forth.

In testimony that I claim the foregoing as my own I have hereunto affixed my signature in presence of two witnesses.

RUFUS R. CARTER.
